(57) **CLAIM**

The ornamental design for a rear quarter panel for vehicles as shown and described.

DESCRIPTION

1. Rear quarter panel for vehicles

1.1 : Perspective

1.2 : Perspective

1.3 : Front

1.4 : Back

1.5 : Left

1.6 : Right

1.7 : Top

1.8 : Bottom

Novelty is claimed in the features of shape and configuration of the rear quarter panel for vehicles shown in the accompanying drawings; the color is not to be claimed; the characteristic features of the design lie in the shape; Fig. 1.1 is a front, right and top side perspective view showing our new design; Fig. 1.2 is a rear, right and top side perspective view thereof; Fig. 1.3 is a front elevation view thereof; Fig. 1.4 is a rear elevation view thereof; Fig. 1.5 is a left side elevation view thereof; Fig. 1.6 is a right side elevation view thereof; Fig. 1.7 is a top plan view thereof; and Fig. 1.8 is a bottom plan view thereof.
